UNITED STATES PATENT OFFICE

MURDOCK MACDONALD, OF CLEVELAND, OHIO

TICKET BOX

Application filed May 5, 1927. Serial No. 189,086.

The principal object of this invention is to provide a novel ticket box, which can be used to facilitate the issuing of tickets of that type which is commonly used as transfers from one street car or bus line to another.

Another object is to provide a device of the class described which will be easy to use, which will not readily get out of order, and the operation of which will be readily understood by anyone who may have occasion to use it.

To the accomplishment of the foregoing and related ends, said invention then consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawings:

Fig. 1 is a top plan view of the box, showing the manner in which the tickets project therefrom; Fig. 2 is a vertical sectional view through said box; Fig. 3 is a bottom plan view thereof, the lower cover having been removed; Fig. 4 is a vertical sectional view of the device taken on the line 4—4 of Fig. 2, and looking in the direction of the arrows; Fig. 5 is a sectional view taken substantially on the line 5—5 of Fig. 2, and looking in the direction of the arrows; Fig. 6 is a sectional view taken substantially on the line 6—6 of Fig. 2, and looking in the direction of the arrows; Fig. 7 is a section on the line 7—7 of Fig. 2 and looking in the direction of the arrows; Fig. 8 is a view of a ticket as it is supplied to the user of my invention; and Fig. 9 is a view showing a detached ticket, and a fragment of the remaining stub.

In the operation of public utility transportation lines, it is necessary to issue transfer tickets to passengers who wish to go from one car to another. These transfer tickets, or transfers, as they usually are called, are ordinarily strips of paper having printed thereon, certain identifying legends such as the time of day, the date, the lines from and

to which they have been issued for use, the junction at which the passenger must change cars, etc.

In the drawings forming a part of this application, I have shown a transfer, the only legend on which relates to time, but it will be obvious that my invention contemplates the use also of transfers bearing other legends, either singly or in combination.

According to established custom, the conductor of a street car or bus carries a number of pads of transfers and a punch, and, when a transfer is requested, he punches the transfer in the appropriate places, tears it off his pad and hands it to the passenger. Several objectionable features are inherent in this system, among which the most prominent is the fact that no identifying stub remains on the transfer pad after a transfer has been issued. Thus a conductor can, without detection, and frequently does, to accommodate a friend, punch a transfer inaccurately and issue it. In this manner, a passenger may ride downtown in the morning, obtain a transfer from a friendly conductor, and ride home on a parallel line in the evening without paying a second fare. My invention eliminates this possibility by providing means whereby a stub corresponding to each issued transfer is left in the box for the inspection of the proper officials at the end of the run. Furthermore, my invention does away with the awkwardness and cumborness involved in the use of a punch and provides means whereby, after a simple setting operation, the mere act of tearing the transfer from the box marks it properly for use.

My invention contemplates the provision of a box 1, having its bottom wall 18 mounted upon a support 3, which support may be fastened, as at 4, to a portion 5 of a street car or bus in such a position as to be convenient to the attendant. The upper portion of the box 1 is pivotally attached by the pin 2 to the said bottom wall, and within said box, and also pivoted on the pin 2, there is mounted a follower plate 6 which is urged toward the bottom of the box 1 by a V-shaped leaf spring 7, one end of which bears against

the follower 6 and the other end of which is fastened to the upper wall of the box 1. The free end wall of the box 1 is part cylindrical in shape, as at 8 for a reason to be later set out, and the lower edge of said wall is formed with an outwardly projecting foot 9, the outer edge of which is dentate in form as is clearly shown at 10 in Fig. 5.

Mounted for rotation in ears 11 and 12 projecting upwardly from the upper wall of the box 1, is a screw 13 of coarse pitch, and threaded upon said screw is a curved arm 14, conforming generally to the shape of the end wall 8 of said box, and the free end of said arm is bent outwardly to form the sharply pointed projection 15. The screw 13 is adapted to be operated by a knurled knob 17.

The box 1 is provided at the lower edge of each of its side walls with an inturned flange 16, as is clearly shown in Figs. 3 and 6. The bottom wall 18 of the box 1 is provided near its free end with downwardly projecting bored lugs 19 and a bent plate 20 is hingedly mounted on said wall 18 through the medium of lugs 19, similar lugs 21 on said plate 20, and a pin 22. A coiled spring 22', one end 23 of which bears against the wall 18, and the other end 24 of which bears against the plate 20, tends normally to hold the latter in the position illustrated in full lines in Fig. 2. Near the outer end of wall 18 is a channelled member 25, attached to the under side of said wall and extending there-across, and slidably mounted in said member 25 are two latch members 26 having bevelled ends 27. A lug 28, depending from each of said members, extends through a slot 29 in said channel member. A coiled spring 30, mounted between said latch members, urges them in opposite directions.

Mounted for rotation in bearings in opposite end walls of the support 3 is a screw 31 having threads of coarse pitch, and having a polygonal end 32 extending outwardly from said support. A knurled knob 33 is formed with a socket adapted to receive said end 32, and is fastened thereto by means of a set screw 34. Non-rotatably mounted on said screw 31 immediately within the support 3 is a disk-like collar 35 which is formed on its periphery with diametrically opposed indentations 36 for coaction with an appropriately shaped leaf spring 37 carried by the support 3. A cover 38 is attached by screws 39 or other means to the support 3 to exclude dust and dirt from the chamber in which the screw 31 is mounted.

Registering slots are formed in the bottom wall 18 of the box 1 and the top wall 40 of the support 3, and a lug 40 depending from a plate 41 is mounted to work in these slots. The plate 41 is slidably mounted on the wall 18 of the box 1 and carries a pair of upstanding pins 42. A pin 43, passing through an aperture in the lug 40, holds the plate 41

against possible upward movement, said pin bearing against the upper wall 44 of a hollowed-out portion of a block 45. Two rods 46 are mounted in said support, and block 45 is slidably mounted on said rods by means of apertures 47 in said block. A third aperture 48 receives said screw 31 and a pin 49 mounted in said block effects screw-threaded connection between said screw and said block. As will be obvious the rods 46 hold the block 45 against rotation.

An example of the type of tickets contemplated by my invention is illustrated in Fig. 8. The ticket comprises a strip of paper 53 having a pair of apertures 54 near one end, and bearing a legend 55 on its face. In the illustrated example, I have shown a ticket which carries on its face merely a table to indicate the time at which it was issued, but it is to be understood that any other type of table might also be used. In the illustrated instance, the black-face numerals indicate hours, while the light face numerals to the right of each hour, indicate quarter hours thereafter.

The operation of my invention may be described as follows: Presuming that the box is closed and empty, the attendant presses inwardly on the lugs 28, thus moving the latch members 26 toward each other against the force of the spring 30, and releasing them from engagement with the flanges 16. The upper portion of the box 1 may now be swung upwardly upon the hinge 2, exposing the plate 41. The follower 6 is of such dimensions that its free end is supported, at that time by the flanges 16. The attendant then places a pad of the tickets or transfers 53 in the box, passing the pins 42 through the apertures 54, and swings the upper part of the box 1 back into position. In this movement, of course, the edges of the flanges 16 cooperate with the bevelled ends 27 of the latch members 26 to force said members toward each other until the flanges have passed beneath them, after which the spring 30 causes said latch members to fly back into position to latch the upper part of the box in place.

When a passenger asks for a transfer at, say, 2:45, the attendant manipulates the knurled knob 33 to shift the plate 41 either to the right or to the left in Fig. 2 until the dentate edge 10 of the foot 9 reaches the position shown in Fig. 5. He then manipulates the knurled knob 17 to shift the arm 14 either upward or downward in Fig. 1 until the projection 15 covers the light-faced numeral 45 following the black-faced numeral 2, as shown in Fig. 5. Then, grasping the free end of the topmost transfer, he tears it across on the line defined by the foot 9 and the projection 15. Fig. 9 aptly illustrates the resultant transfer and stub, from either of which one can easily and quickly note the time at which the transfer was issued. It should be noted

here that the relation of the threads of the screw 31 to the indentations 36 of the collar 35 is such that the spring 37 drops into an indentation each time the edge 10 of the foot 9 aligns with the lower edge of a row of numerals on the transfer face, thus insuring against careless or faulty manipulation of the screw 31.

Of course, it is obvious that if no provision were made against it, the stubs of various lengths left on the pad after the issuance of a number of transfers would seriously interfere with the manipulation of the illustrated device. In order to overcome this difficulty, I have provided means whereby the stubs are always kept out of the way.

After the attendant issues a transfer, he manually depresses the upper part of the box 1 to, or nearly to, the position illustrated in dotted lines in Fig. 2. This operation swings the plate 20 downwardly on its pivot, and causes the foot 9 to slide along the face of the stub, and past its end. When the attendant releases the pressure on the upper part of the box, the latter is swung back to the position illustrated in full lines in Fig. 2 by the force of the spring 7, while the plate 20 is swung back to its original position by the force of the spring 22. By reason of the angle at which the inner face of the end wall of the box 1 meets the transfer stubs, the stub ends will ride up along said inner face in the manner illustrated in Fig. 2.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. A ticket box comprising a bottom wall, means carried by said wall for holding a pad of tickets, a box-like member pivoted to said wall at its one edge, means for holding the opposite edge of said member in contact with the uppermost ticket of such pad, a follower pivoted within said member and adapted to overlie such uppermost ticket, and a spring in said member and urging said follower against such ticket.

2. A ticket box comprising a bottom wall, means carried by said wall for holding a pad of tickets, a pivot pin mounted at each end of said wall, an upper member pivoted on one of said pins, a follower pivoted to the same pin and enclosed by said upper member, a spring carried by said upper member and bearing on said follower, said upper member having an outturned, dentate foot extending from its free end, a screw mounted on said upper member, an arm threaded to said screw and terminating in an outturned pointed projection adjacent said foot, a plate

pivoted to the other of said pins, a spring normally urging said plate toward said upper member, spring pressed latch members carried by said wall, and inturned flanges formed on said upper member for co-operation with said latch members.

3. In combination with a ticket box and means in said box for holding a pad of tickets, a support carrying said box and means journalled in said support for shifting said holding means longitudinally of said box.

4. In combination with a ticket box and means in said box for holding a pad of tickets, a support carrying said box, a screw journalled in said support, a projection depending from said holding means and threadedly engaged with said screw, a collar on said screw having an indentation in its periphery, and a spring mounted in said support for co-operation with said indentation.

5. In combination with a ticket box and shiftable means in said box for holding a pad of tickets, a support carrying said box, a screw journalled in said support, a projection depending from said holding means and threadedly engaging said screw, and means for stopping said screw at predetermined points in its rotation.

6. The combination with a ticket box having a slotted bottom wall and a support having a slotted upper wall, said box being mounted upon said support, of a plate slidably mounted on said bottom wall, pins extending upwardly from said plate, a projection depending from said plate, and extending through said slots into said support, a screw journalled in said support, and having threaded engagement with said projection, and means in said support for stopping said screw at predetermined points in its rotation.

7. In combination, a support, having a slotted upper wall, a box mounted on said support and having a slot in its bottom wall and registering with said first-named slot, a plate slidably mounted in said box, pins extending upwardly from said plate, a projection depending from said plate and extending through said slots, a screw in said support, a member attached to said projection and threadedly engaged with said screw, and means in said support for preventing the rotation of said member.

8. In combination with a ticket box enclosing a plate adapted to hold a pad of tickets, a second plate pivoted to the bottom wall of said box and adapted to support the outer ends of said tickets, a spring for normally holding said second plate in raised position, a pin pivotally connecting the upper portion of said box to said bottom wall, a follower in said box, a spring carried by said upper portion of said box and bearing on said follower, an end wall of said upper por-

tion being adapted to bear on said tickets, said end wall being part cylindrical in shape whereby when the free end of said upper portion is depressed, and then released, the short stubs of torn tickets will be thrown into and completely enclosed by said upper portion.

9. In a device for issuing tickets and adapted to enclose a ticket having a plurality of apertures at one end and a legend approximately midway of its length, a box comprising a bottom wall carrying a slidable plate and an upper portion pivoted at one end to said wall, a plurality of pins extending upwardly from said plate and adapted to be engaged in the apertures of a ticket, such ticket extending out of the box, a follower plate pivoted in said box and adapted to bear on such ticket, a spring in said box between said follower and said upper portion, a flange on said upper portion, a latch member on said bottom wall for co-operation with said flange, said upper portion being formed with a curved end wall provided with an outwardly extending dentate foot, a plate pivoted to the outer end of said bottom wall and forming a support for the projecting end of a ticket, a coiled spring urging said plate upwardly and said ticket into contact with said foot, and means for shifting said slidable plate longitudinally of said wall.

10. In a construction as set out in claim 9, ears projecting from the free end of said upper portion, a screw journaled in said ears, and a curved arm, terminating in an out-turned pointed end adjacent said foot, threaded to said screw.

11. In a ticket box, the combination of a box-like casing open at one side, a plate hinged to one edge of such open side of said casing, means for mounting said plate, a ticket carrier shiftably mounted on said plate, a second plate hinged to said first-named plate, means for pressing said second plate toward the other edge of said casing, said second plate being positioned normally at a slight angle to the first plate, thereby effecting a slight arch in the pad of tickets interiorly of the last-named casing edge.

12. A ticket box comprising a bottom wall, a pivot pin mounted at one end of said wall, an upper member pivoted on said pin, means limiting relative swinging movement of said wall and member away from each other, a follower pivoted to said pin between said wall and said member, and a spring in said member urging said follower toward said wall.

13. In a ticket box, the combination of a box-like casing open at one side, one end thereof being curved outwardly from the adjacent edge of such open side, a plate hinged to the other edge of such opening, a second plate hinged to said first plate, a spring pressing said second plate toward said first-named

edge, and a ticket carrier shiftably mounted on said first-named plate.

14. In a ticket box, the combination of a box-like casing open at one side, one end thereof being curved outwardly from the adjacent edge of such open side, a plate hinged to the other edge of such opening, a second plate hinged to said first plate, a spring pressing said second plate toward said first-named edge, a ticket carrier shiftably mounted on said first-named plate, a ticket pad mounted on said carrier, and a spring bearing on the top of said ticket pad in line with the hinge point of said plates.

15. In a ticket box, the combination of a box-like casing open at one side, one edge of said open side being formed to provide a tearing edge and the side contiguous said edge being curved outwardly to provide an inner compartment forward of said edge, a plate hinged to the other edge of such opening, a second plate hinged to said first plate, a ticket carrier shiftably mounted on said first plate adapted to position a pad of tickets with the ends thereof projecting between said second plate and the tearing edge.

16. In a ticket box, the combination of a box-like casing open at one side, one edge of said open side being formed to provide a tearing edge and the side contiguous said edge being curved outwardly to provide an inner compartment forward of said edge, a plate hinged to the other edge of such opening, a second plate hinged to said first plate, a ticket carrier shiftably mounted on said first plate adapted to position a pad of tickets with the ends thereof projecting between said second plate and the tearing edge, and a spring mounted in the interior of said casing and bearing on the pad of tickets adjacent the hinge point of said plates whereby a slight arch is effected on the uppermost tickets about that point.

Signed by me this 4th day of May, 1927.

MURDOCK MACDONALD.
